UNITED STATES PATENT OFFICE

99,311

DESIGN FOR A FINGER RING

Abraham Sager, Chicago, Ill.

Application February 16, 1935, Serial No. 55,471

Term of patent 14 years

To all whom it may concern:

Be it known that I, Abraham Sager, a citizen of the United States, and resident of Chicago, in the county of Cook and State of Illinois, have invented a new, original, and ornamental Design for a Finger Ring, of which the following is a specification, reference being had to the accompanying drawing forming a part thereof.

In the drawing,

Fig. 1 is a perspective of a ring embodying my new design which is similar and continuous about the ring;

Fig. 2 is a developed plan view of a portion of the ring shown in Fig. 1, bringing out the details of the design; and

Fig. 3 is an enlarged section through one of the conventional leaves of the design as taken on the line 3—3 of Fig. 2.

I claim:

The ornamental design for a finger ring as shown and described.

ABRAHAM SAGER.
